Primary Examiner — Andrew Kerr

(57) **CLAIM**

The ornamental design for a coffee tool as shown and described.

DESCRIPTION

FIG. 1 is a front and top perspective view of a coffee tool, showing my new design;

FIG. 2 is a rear and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is an enlarged view of an encircled area labeled “9” in FIG. 2.

The short-dash long dash broken lines framing portions of the claimed design that are illustrated in enlargements form no part of the claimed design.
